The ornamental design for an electric actuator, as shown and described.

DESCRIPTION

FIG. 1 is a front perspective view of the front, left, and top sides of an electric actuator showing our new design;

FIG. 2 is a rear perspective view of the rear, right, and bottom sides thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is an enlarged view of a part 9 of FIG. 1;

FIG. 10 is a perspective view showing a state where a rod is retracted; and,

FIG. 11 is a perspective view showing a state where a rod is extended.

The broken lines show portions of an electric actuator that form no part of the claimed design.

The dash-dot-dot broken lines in FIG. 1 represent the boundaries of the enlarged view seen in FIG. 9, and form no part of the claimed design.
